[57] **ABSTRACT**

An assembly for use in electrolysis cells including a permanent, rigid, inert and reusable base which has the form of a square open tank with only three sidewalls; and, an anodic aggregate set down on this base without an fastening means. This aggregate is composed of graphite anodic plates, anodic bars and the fourth sidewall of the base. All metallic parts of the assembly are protected by a covering which also embodies the fourth sidewall. The tightness between the fourth sidewall and the base is insured by a flexible seal.

ANODIC ASSEMBLY FOR ELECTROLYSIS CELLS

This invention concerns a new anodic assembly for electrolysis cells where anodes and cathodes are interleaved and are especially used to electrolyze aqueous solutions of alkaline metal halogenides.

In conventional cells of this type, the anodic plates are made of graphite and are vertically settled in a reinforced concrete base. They are set in a bed made of lead or a low melting point alloy. Conductive bars supply the electric current and are embedded in contact with the bottom of the anodic plates. An inert covering protects this lead or alloy bed against an attack of the electrolyte or of the electrolysis products. When used, the anodic plates become thinner and thinner and must be replaced periodically. However, the lead or alloy and the conductive bars may only be recovered by destroying the base.

Belgian Pat. Nos. 674,452 and 708,888 relate to improvements to conventional assemblies. These improvements consist essentially in melting the embedding material by means of the Joule effect, and then using a low melting point alloy, such as a lead-bismuth alloy. These alloys are much more expensive than lead which is generally used as the embedding material, and the materials used to manufacture the base must withstand the melting temperature of the alloy. Finally, the assembly must be sealed where the conductive bars cross one side wall of the base.

Objects of the present invention include: the provision of an anodic assembly in which the anodic bars and the embedding may be easily recovered without destroying the base of the cell; the provision of an anodic assembly where pure lead may be used as an embedding material; the provision of an anodic assembly which does not require a heat resistant base for extremely high temperatures; and, the provision of an anodic assembly which does not require special sealing means where the conductive bars come out of the base.

In the anodic assembly of the invention, cathodic and anodic elements are interleaved and supported in a base. The base is an open quadrangular rigid tank of which one of the sidewalls is missing. The anodic aggregate comprises vertical anodic plates made of graphite, anodic conductive bars, and the fourth sidewall of the base, and said aggregate without any fastening means is set down on the base. The anodic conductive bars convey the electric energy to the anodic plates and cross the fourth sidewall of the base. The base is provided with a protective covering for withstanding the electrolyte and the electrolysis products, and the anodic aggregate, except the unembedded part of the anodic plates and the projecting parts of the conductive bars, is enclosed in a rigid inert envelope. The tightness between the anodic aggregate and the base is insured when the fourth sidewall fits into the base by means of a flexible seal made of a closed cell cellular material laid in a groove provided in the base.

The accompanying drawings illustrate the invention. In such drawings:

FIG. 1 is a perspective view of a base according to the invention;

FIG. 2 is a perspective view of an anodic aggregate which fits into the base represented in FIG. 1;

FIG. 2A is a sectional view taken along line A—A of FIG. 2;

FIG. 2B is a sectional view taken along line B—B of FIG. 2;

FIG. 3 is a perspective view of the anodic aggregate represented in FIG. 2 set down in the base represented in FIG. 1;

FIG. 4 is a detail view of the flexible seal and its receiving groove before the anodic aggregate is set down; and

FIG. 5 is a detail view of the flexible seal and groove after the anodic aggregate has been set down.

The anodic assembly illustrated in the drawings is particularly adapted for use as part of a diaphragm electrolysis cell used to electrolyze aqueous solutions of sodium chloride and in another electrochemical process. The base, as shown in FIG. 1, is made of reinforced concrete, and is provided with a synthetic resin coating for withstanding the chlorinated brine. The base comprises a structure having a rather square bottom

1 and three sidewalls 2. The fourth sidewall 3 (see FIG. 2) is removable and forms a part of the anodic aggregate. A flexible seal 4, made of a closed cell cellular material for withstanding the chlorinated brine, is placed between the fourth sidewall 5 and the base. The seal has a rectangular cross section and it is laid in the flat bottom groove 5 of the base. The sealing edge of the fourth sidewall is provided with an angular ledge 6, having a triangular section, as shown in FIG. 2. The ledge presses on the seal 4 perpendicularly to the bottom of the groove 5, and its two oblique faces press the seal against the edges of the groove 5. Thus, the ledge 6 and the groove 5 combine to provide a very efficient seal by effectively forming three sealing edges of compression on the flexible seal 4. That is, sealing edges are formed by pressure of the apex of the ledge on the flexible seal 4, and by the pressure of said flexible seal against the corners of the groove 5 as caused by the oblique faces of the ledge.

The anodic aggregate (see FIG. 2) comprises essentially vertical anodic plates 7, anodic bars 9 (see FIG. 2A), embedding metal 10, connecting crosspieces made of copper 8, and the fourth sidewall 3 of the base illustrated in FIG. 1. The anodic plates 7 are made of graphite and are aligned in parallel rows. The rows are spaced to let the cathodic elements interleave with them. The bottoms of the anodic plates are embedded in lead 10, and said plates are supported on anodic bars 9 which convey electrical energy to the plates. The bars 9 are made of copper and are connected with the crosspieces 8 which pass through the fourth sidewall 3. Thus, the anodic aggregate is an alignment of independent anodic units each of which comprises a crosspiece 8, an anodic bar 9 two rows of anodic plates 7 and the embedding metal 10, and said anodic units are separated at their lower portions by sheets of plastified polyvinylchloride 11.

35 With the exception of the crosspieces 8 and the graphite plates 7, the entire anodic aggregate is provided with an external protective envelope which is made of a charged polyester resin, and which withstands the chlorinated brine.

The fourth sidewall 3, which is integral with the anodic aggregate, encloses strengthening elements 12,13 made of rigid expanded material, as shown in FIG. 2B. These elements 12,13 are laid respectively between and above the crosspieces 8, and they confer rigidity to the aggregate. Said elements also provide a saving of polyester resin and make the aggregate lighter. Their dimensions are preferably controlled so that the thickness of the polyester envelope is essentially constant, and tensions due to the thermal expansion are thus avoided.

The anodic aggregate and the base are assembled without any binding material or fastening means. The aggregate is simply set down on the base and held in place only by gravitational force. The electrolysis brine may penetrate without damage between the aggregate and the base, and an effective seal between the fourth sidewall 3 and the base is realized automatically by the resultant compression of the flexible seal 4 when the aggregate is set down. Thus, there is no need to attempt to make a seal around the crosspieces 8 which make one piece with the sidewall 3.

When the anodic plates are consumed, the anodic aggregate is lifted from the basement by simple lifting means and a new one is set down. This change does not require any destruction and may be done very quickly. Only the envelope must be destroyed to recover the anodic bars 9 and the embedding material 10 in the anodic aggregate while the base may be continually reused.

What I claim is:

1. An anodic assembly for electrolysis cells in which anodes and cathodes are interleaved, comprising a base consisting essentially of a rectangular bottom and three upstanding sidewalls at three sides only of said bottom, said base having an open side at the fourth side of said bottom defined by an opening having a bottom edge extending along said fourth side of said bottom and two inclined side edges sloping up and joining adjacent sidewalls of said base; and an anodic aggregate comprising horizontal conductors, vertical anodic elements

set down on said conductors in conductive relation therewith, embedding material embedding said conductors and lower portions of said anodic elements to unit them in a unit, a fourth side wall unitary with said unit and cross-connectors embedded in said material, connecting said conductors and extending out through said fourth sidewall, said anodic aggregate being set down on said base over said bottom with said fourth sidewall fitting in said opening, and a flexible sealing gasket disposed between lower and side edges of said fourth sidewall and said bottom and side edges of said opening to provide a fluid tight seal therebetween, said anodic assembly being removable from said base and replaceable by a like anodic assembly.

2. An anodic assembly according to claim 2, wherein said bottom and side edges of said opening are formed with a channel in which said gasket is sealed and wherein the bottom and side edges of said fourth side are of V-cross section to press into said gasket.

3. An anodic assembly according to claim 2, wherein said channel is of rectangular cross section.

4. An anodic assembly according to claim 2, wherein said gasket is of closed cell cellular material.

5. An anodic assembly according to claim 1, wherein said embedding material comprises lead.

6. An anodic assembly according to claim 5, wherein said anodic aggregate comprises an assembly of units of which corresponding portions of said embedding lead are separated from one another by sheets of plastified polyvinylchloride.

7. An anodic assembly according to claim 1, wherein said base is of concrete covered with a synthetic resin coating resistant to chlorinated brine.

15 8. An anodic assembly according to claim 1, wherein said fourth sidewall comprises strengthening elements of rigid expanded material.
